CLAIM

The ornamental design for a tool handle, as shown and described.

DESCRIPTION

FIG. 1 is a front, top and side perspective view of the tool handle embodying my new design;

FIG. 2 is a front end elevational view thereof, taken from the left end FIG. 1;

FIG. 3 is a rear end elevational view thereof, taken from the right end in FIG. 1;

FIG. 4 is a side elevational view thereof, the side opposite being a mirror image of the side shown in FIG. 4;

FIG. 5 is a top plan view thereof; and,

FIG. 6 is a bottom plan view thereof.

1 Claim, 3 Drawing Sheets

FIG.1.

FIG. 2.

FIG. 6
